UNITED STATES PATENT OFFICE

ADOLPH COORS, OF GOLDEN, COLORADO

DESIGN FOR A MALTED MILK CONTAINER

Application filed July 13, 1931. Serial No. 40,532. Term of patent 14 years.

To all whom it may concern:

Be it known that I, ADOLPH COORS, a citizen of the United States, residing at Golden, in the county of Jefferson and State of Colorado, have invented a new, original, and ornamental Design for Malted Milk Containers, of which the following is a specification, reference being had to the accompanying drawings, forming part thereof.

Fig. 1 is a front view of my container for use in storing and dispensing malted milk or the like; and

Fig. 2 is a side elevation showing my improved design.

The container is intended for use in connection with soda fountains for storing and dispensing malted milk or the like and consists of a short hollow cylindrical vessel having one side provided with a base and the other side with an opening. The container has a movable cover that serves to close the opening and which is held in closed position by means of a spring.

I claim:

The ornamental design for a malted milk container, as shown and described.

In testimony whereof I affix my signature.

ADOLPH COORS.
